HOOD CATCH

Filed May 3, 1928

INVENTOR.
RAYMOND G. MOORE.
BY
James Mathew.
ATTORNEY

UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT

HOOD CATCH

Application filed May 3, 1928. Serial No. 274,818.

The present invention relates to automobile hood catches, and has for an object to provide an improved latch of the type adapted in addition to holding down the hood, to also force the same inwardly, and thereby effectively secure it against looseness and rattling. A further object is to provide such a catch which will compensate for variations in the position of the hood, so that wear and inaccurate placing of the catch will not affect its proper functioning. Another object is to provide a catch in which there will be metal to metal contact between the compensating parts, but so arranged and cooperating as to always maintain a non-rattling relation, free of squeaks and scraping noises, and to this end it is particularly proposed in the present embodiment to provide a compensating keeper upon the hood yieldable in parallel relation with the hood, and adapted to permit downward pulling movement of the catch, at all times maintaining a tight non-rattling engagement between the catch and the keeper; and further to provide a cooperative camming means between the hood and catch adapted to produce both a downward and inward pressure.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a side elevation, partly in section of a hood catch, according to the present embodiment of the invention, the catch being disengaged;

Fig. 2 is a front elevation of the keeper and hood;

Fig. 3 is a side elevation, showing in dotted lines the initial engaging position with the keeper, and in full lines, the final or operative engaging position.

Fig. 4 is a side elevation of a modified form of the invention.

Referring to the drawings, the hood catch, according to the present embodiment of the invention, consists of a cylindrical barrel 10,

flanged at its lower end, as at 11, to provide a reduced passage in which a rod 12 is slidably engaged, the end of the rod within the barrel being provided with a fixed washer 13, between which and the flange 11 a spring 14 is coiled about the rod.

The lower end of the rod 12 has a head or upset 15, engaged in a dome-shaped slotted base member 16 secured to the sill-piece of the automobile frame.

The upper end of the barrel is threaded as at 17, and is screwed into the threaded socket 18 of a cap member 19, which closes the upper end of the barrel and forms a stop to limit the upward movement of the rod 12 under the pressure of the spring. A clamping hook 20, and a handle 21, are formed integrally with the cap member.

The keeper comprises an elongated base plate 22, riveted to the hood, and having secured to its upper portion a plate 23 having spaced vertically disposed tubular barrel portions 24 and 25 bent therefrom, the upper and lower ends of these portions being flanged inwardly as at 26 to provide reduced guide apertures, in which the side legs of an inverted U-shaped sliding keeper 27 are engaged. Springs 28 and 29 are respectively provided on the side legs between the lower flanges 26 and washers 30 secured upon the side legs beneath the upper flanges 26, and adapted to normally press the sliding keeper upwardly and permit downward yielding movement in parallel relation to the hood. The upper transverse portion of the sliding keeper is bent outwardly, as at 31, for engagement by the hook end 20 of the catch. The hook end 20 has a relatively large radius and is substantially wider at its under hooking surface than the portion 31 so that when engaged lateral play is permitted between them.

An inclined cam portion 32 is formed up from the base 22 of the keeper as its lower end, and upon the hood catch barrel there is provided a projecting cam lug 33, having an inclined engaging face 34 adapted in the engaged relation of the catch to engage and bear upon the cam portion 29.

The operation is as follows:

As shown in Fig. 1 the catch is contracted,

the sliding keeper being raised. The catch is pulled upwardly against the pressure of the spring to a point permitting engagement with the keeper, and is thereupon released, the sliding keeper yielding downwardly to a position as shown in full lines Fig. 3, the barrel moving downwardly and pressing the cam lug 33 into engagement with the cam portion 32, so that both a downward and an inward force or pressure is exerted upon the hood to securely clamp it in closed position. The sliding keeper, through the action of its springs always maintains a tight non-rattling relation with the catch, irrespective of wear and irregularities, the actual holding downwardly and inwardly of the hood being through the cooperation of the cam surfaces 31 and 34, the relative inward pressure on the hood being permitted through the lateral play between the keeper and clamp.

In Fig. 4, I have illustrated a modified form of the invention in which an upwardly extending inclined cam lug 35 is provided on the base of the keeper, and which is engaged by a cam portion 36 on the barrel having a relatively long inclined under surface. The function and operation is the same as in the first embodiment.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters Patent is:—

1. In a hood catch or the like, a hold down clamp, a keeper yieldable downwardly in parallel relation to the hood adapted to be engaged by said clamp and permitting lateral play between said keeper and said clamp, spring means acting to draw said clamp downwardly and move said keeper downwardly and cam means between said clamp and the hood adapted to press the hood downwardly and inwardly under the action of said spring means.

2. In a hood catch or the like, a hold down clamp, a keeper including a base adapted to be mounted on the hood and a movable part yieldable downwardly in parallel relation with the hood and including a clamp engaging portion outwardly spaced from the hood adapted to be engaged by said clamp and permitting lateral play between said keeper and said clamp, spring means acting to draw said clamp downwardly and move said keeper downwardly and cam means between said clamp and the hood adapted to press the hood downwardly and inwardly under the action of said spring means.

3. In a hood catch or the like, a hold down clamp, a keeper including a base adapted to be mounted on the hood and a movable part yieldable downwardly in parallel relation

with the hood and including a clamp engaging portion outwardly spaced from the hood adapted to be engaged by said clamp and permitting lateral play between said keeper and said clamp, means adapted to normally retain said movable part in raised position and permitting yielding downward movement whereby said clamp engaging portion remains in snug engagement with the clamp, spring means acting to draw said clamp downwardly and move said keeper downwardly and cam means between said clamp and the hood adapted to press the hood downwardly and inwardly under the action of said spring means.

4. In a hood catch or the like, a hold down clamp, a keeper yieldable downwardly in parallel relation to the hood adapted to be engaged by said clamp and permitting lateral play between said keeper and said clamp, spring means acting to draw said clamp downwardly and move said keeper downwardly, and cam means between said clamp and the hood comprising an inclined cam surface on one of them and a cam projection on the other, adapted to press the hood downwardly and inwardly under the action of said spring means.

Signed at Bridgeport, county of Fairfield, and State of Connecticut, this 20th day of April, 1928.

RAYMOND G. MOORE.
